UNITED STATES PATENT OFFICE.

FRANK B. MALLORY, OF FLEMINGTON, NEW JERSEY.

SHUTTER-FASTENER.

SPECIFICATION forming part of Letters Patent No. 374,981, dated December 20, 1887.

Application filed July 19, 1887. Serial No. 244,757. (No model.)

To all whom it may concern:

Be it known that I, FRANK B. MALLORY, a citizen of the United States, residing at Flemington, in the county of Hunterdon and State 5 of New Jersey, have invented certain new and useful Improvements in Shutter - Fastening Bars, Bolts, and Operating Mechanisms; and I do hereby declare the following to be a full, clear, and exact description of the invention, 10 such as will enable others skilled in the art to which it appertains to make and use the same.

My invention relates to an improved shutter-bar-fastening bolt or rod, and to mechanism whereby the shutter-fastening bolt and 15 the bar are moved in and out of locking and fastening position from the inside of a room without opening the window and without manipulation from the outside of the building.

In the accompanying drawings, Figure 1 is 20 a view of a pair of shutters with a window-frame and a portion of the surrounding wall provided with the fastening shutter-bar and my operating mechanism. Fig. 2 is a horizontal section through the fulcrum portion 25 of the bar and the adjacent parts of the building. Fig. 3 is a view of a modified construction of the fulcrum-shaft; and Fig. 4 is the shutter-bar fastener, shown in two different 30 positions, one in full lines and the other in dotted lines.

The letter A in the drawings represents an ordinary window-frame, a a sashes, B B shutters, and C a shutter-fastening bar.

The shutter-fastening bar C is firmly attached 35 to the square head d of a fulcrum-shaft, D, which is fitted in the vertical portion a' of the window-frame and extends into the room of the house, where it is provided with a crank or a more elegant operating device—as, for instance, a hand-wheel, d'—which latter serves 40 as the means for swinging the bar C across the shutters, as shown by full lines, or away from and out of range of the shutters, as shown in dotted lines in Fig. 1.

The end of the bar C while in a horizontal 45 position, is supported and held fast by a stepped hook, d², formed at the end of a sliding lock bolt or rod, D'. The step d³ of the hook d² is provided with an upper outwardly- 50 inclined projection, d⁴, whereby the end portion of the bar C is guided in its descent into the hook d². The fastening bolt or rod

D' is fitted into the vertical portion a² of the window-frame, and is at the inner side of said frame provided with a cylindrical end portion, d⁵, having an annular groove, d⁶. To the end portion d⁵ a handle, E, is fitted, which has an inclined face, e, and set-screw e', the latter extending into the groove d⁶, so that the handle can be turned around the portion d⁵ 55 without sliding off longitudinally. Between the handle E and window-frame a hollow boss, e², having a flange, e³, and an inclined face, e⁴, is placed. Through the boss e² the fastening bolt or rod D' passes, and thus the inclined 60 faces e and e⁴ stand opposite each other and cause the said bolt or rod to be drawn against the bar C when the handle E is turned down, as in Fig. 4, and when the handle E is turned up, as indicated by dotted lines in the same 65 figure, the fastening bolt or rod D' becomes released and may be pushed out by hand or by a suitable tension-spring, thereby moving the hook d² sufficiently away from the bar C to permit its swinging up to the position shown 70 by dotted lines in Fig. 1, in order to fasten the shutters.

For the purpose of facilitating the operation of raising the bar C a balance-weight, F*, is, 75 by means of a cord or chain, f, attached at a suitable place, f', to the bar, the cord f being suspended on a pulley, f², fixed to the window-frame, and the weight F* moving in a guiding and protecting tube, f³, suitably fastened to the wall or window-frame.

When the window-shutters are to be opened, the handle E is turned up and the bolt or rod D' pushed outwardly. The hand-wheel d' is then turned and the bar C turned up in the position indicated by the dotted lines, and the 80 shutters can now be swung open by means of inside - operated shutter - workers, as at a³, which may be of any well-known construction. When the window-shutters are to be locked, they are first closed together, then by means 85 of the hand-wheel d' the bar C is turned down into the hook d², whereupon the handle E is turned down, the hook d² drawn against and partly over the bar C, and thereby said bar C is securely locked across the shutters. This 90 described operation is performed entirely from the inside of the building and without opening windows or shutters.

Instead of the vertically-gravitating weight

F* and pulley f^2 for balancing the bar C, a weight, F, may be used upon a rear extension, e, of the bar C, or a spring, e', coiled around the shaft D and fastened to the bar C and window-frame in a suitable manner, may be successfully employed, and other means than the cam 5 may be adopted for moving the locking bolt or rod D' out of hooking position with the bar C.

10 The fulcrum-shaft D might be provided with an ordinary ratchet and pawl, as d^* d^{*2} , or other suitable device for holding it from being turned after the bar C has been adjusted upon the bolt or rod D', and in such case it 15 would not be necessary to have the hook d^2 overhang the bar. I, however, prefer to have the hook d^2 overhang the bar, as shown.

What I claim as my invention, and desire to secure by Letters Patent, is—

20 1. The combination of the shutter-fastening bar C, pivoted to a fulcrum-shaft, D, which is extended into the room of a building on which the shutters are hung, and is provided with

an operating handle or wheel on its inner end, a mechanical device for holding the bar C in 25 its fastening position, and the bolt or rod D', upon which the bar rests and is confined, substantially as and for the purpose described.

2. A shutter-fastening mechanism operated from the inside of a building, consisting of a 30 swinging bar, C, operating-shaft D, and sliding fastening bolt or rod D', provided with a hook, d^2 , substantially as and for the purpose described.

3. The combination, with outer shutters of 35 a window-frame, of the balanced swinging fastening-bar C and the sliding lock bolt or rod D', having hook d^2 , both operated in the interior of a building, substantially as and for the purpose described.

In testimony whereof I affix my signature in presence of two witnesses.

FRANK B. MALLORY.
